STOCKING

Frederick L. Hall, Snow Shoe, Pa.

Application June 8, 1949, Serial No. 97,807

6 Claims. (Cl. 66—182)

1

The invention relates to stockings, and to the manufacture thereof. It is especially directed to stockings intended for evening wear, having new features which are both useful and ornamental.

The usual type of stocking has either a seam down the back of the leg or a reinforcement in the heel and foot, or both. When these are not properly centered on the wearer's legs, the appearance is sloppy and displeasing. Under normal conditions, it is easy enough to tell whether the stocking is properly positioned, but this is not possible when the wearer is going from darkness into an illuminated area.

The primary object of the invention is to provide a stocking so constructed that the wearer is able to determine, even in darkness, whether a stocking is straight on the leg.

Another object of the invention is to produce a stocking in which this result is achieved by incorporating at proper points, during the manufacture of the stocking, one or more luminescent threads which will glow in the dark.

Still another object of the invention is to provide a stocking which is highly ornamental even in darkness, since the design formed by the luminescent threads is visible even though the remainder of the stocking may be only dimly seen. Such a stocking attracts considerable attention and adds enticement.

A further object of the invention is to embody in the stocking luminescent threads which are so selected as to serve, when the wearer is in an illuminated place, to create a distinctly visible and contrasting seam or pattern in the stocking.

Further objects and advantages of the invention will appear more fully from the following description, especially when taken in conjunction with the accompanying drawings which form a part thereof.

In the drawings:

Fig. 1 is a rear perspective view of a stocking embodying my invention;

Fig. 2 is a side view thereof;

Fig. 3 is a rear view thereof; and

Fig. 4 is a side view of a modification thereof.

The stocking shown in Figs. 1 to 3 has a body formed of a leg portion 2 and a foot portion 4, with a conventional top 6. A seam 8 extends up the back of the stocking, lying in the "fore-and-aft plane" of the stocking, the plane A—A of Fig.

3. The stocking also has a reinforced heel and foot portion 10 of conventional type, this portion ordinarily contrasting in appearance with the body of the stocking because it is formed of more closely knitted threads.

2

According to one phase of the present invention, the reinforcement 10 is outlined by a line or stripe 12. The reinforcement is symmetrical with respect to the fore-and-aft plane, as is the seam, so that the pattern formed by line 12 is also symmetrical with respect to this plane. The pattern may extend as shown down practically to the toe, or it may end at some intermediate point.

According to the present invention, either the seam 8 or some part or all of the pattern line 12, is made luminescent. This is preferably accomplished by incorporating, during the manufacture of the stocking, in a manner well known in the art, a luminescent thread in the body of the stocking. Such a thread is of itself known, and is produced by the inclusion of a suitable luminescent material in the thread. Several threads may be incorporated side by side if a wider line or stripe is desired.

Preferably the pattern so formed is also visible in ordinary light, so as to serve as the usual ornamentation. This may be done by knitting the threads more closely in the pattern than in the adjoining parts of the stocking; or by using threads of different gauge; or by using the threads of different color, or which will assume a different color or shade when the stocking is dyed, or in any other suitable fashion.

The pattern need not be formed of a single line. Fig. 4 shows a pattern composed of a wide stripe 14 along the edge of the reinforcement, which could be four needles wide, and a narrow line 16 spaced slightly from the stripe and within the body of the stocking, which may be two needles wide. One or both of these stripes may be luminescent. Obviously other patterns may be used, as long as they are symmetrical about the fore-and-aft plane of the stocking.

It is clear that such a stocking, in addition to presenting a pleasing appearance either in light or in darkness, also enables the wearer to determine, even in the dark, whether her stockings are askew, and prevents the embarrassment which she might otherwise suffer of entering a lighted room only to discover that her stockings are in an unsightly condition. The invention can be practiced with known machinery without substantial changes therein, and in ways known to operators skilled in the art.

While I have described herein some embodiments of my invention, I wish it to be understood that I do not intend to limit myself thereby except within the scope of the claims hereto or hereinafter appended.

I claim:

1. A stocking having a heel and toe reinforcement symmetrical with respect to the fore-and-aft plane of the stocking, and a luminescent strip outlining said reinforcement.

2. In a stocking as claimed in claim 1, said strip being of contrasting appearance with the body and reinforcement.

3. A stocking having a heel and toe reinforcement symmetrical with respect to the fore-and-aft plane of the stocking, and a strip formed by at least one luminescent thread incorporated in the stocking forming a pattern outlining at least the upper part of said reinforcement.

4. In a stocking as claimed in claim 3, said pattern contrasting in appearance with the adjacent portions of the stocking.

5. In a stocking as claimed in claim 4, a seam extending up the back of the stocking, and at least one luminescent thread incorporated in said seam.

6. In a stocking as claimed in claim 3, a seam

extending up the back of the stocking, and at least one luminescent thread incorporated in said seam.

FREDERICK L. HALL.
